EDWIN BURRITT PROUDFIT, OF WESTFIELD, NEW JERSEY, ASSIGNOR TO THE AEOLIAN COMPANY, A CORPORATION OF CONNECTICUT.

MEANS FOR BOXING MUSIC-ROLLS.

1,317,035.

Specification of Letters Patent. Patented Sept. 23, 1919.

Application filed January 26, 1915. Serial No. 4,567.

To all whom it may concern:

Be it known that I, EDWIN B. PROUDFIT, a citizen of the United States, residing at Westfield, in the county of Union and State of New Jersey, have invented certain new and useful Improvements in Means for Boxing Music-Rolls, of which the following is a specification.

My invention relates to the art of boxing music rolls and the like and to devices useful therein. Heretofore different sized rolls have been boxed in boxes which not only varied in width but in height,—resulting in an uneven, unsightly appearance of the rows of said boxes in a cabinet; or if not in a cabinet, resulting in the uneven, unstable stacking of layers of said boxes on each other. These difficulties and disadvantages are remedied by my invention.

In the drawings Figure 1 is a front view of a row of music-roll boxes within the practice of my invention, the boxes being shown label-end toward the front, with the middle box in vertical cross-section; Fig. 2 is a longitudinal section partly in elevation, of the same box; Fig. 3 is an enlarged cross-sectional view of music roll and box to indicate the working of roll retaining clip; and Fig. 4 is a view partly in section of the bottom block and clip portion of a box; Figs. 3 and 4 are taken on lines 3—3 and 4—4, respectively, of Fig. 2; but in Fig. 4, the cover and body portions of the box are omitted.

Describing now the devices of the drawings, 1 is the body of the box with the usual telescoping top or cover portion 2. The boxes in Fig. 1 are all of the same height in spite of the fact that they contain music rolls of widely different diameters; whereas they are of different widths to conform to said different diameters of the rolls. This still keeps the length of the row the least possible but makes the tops of all the boxes uniform or of the same level.

In box B, the roll rests as usual on the bottom of the regular box-body as indicated by the dotted lines in Fig. 1. Whereas in box A, a raised bottom is provided to elevate the roll into a more accessible position adjacent the mount of the box. This extra bottom consists of a strip of material bent up into the form of an inverted trough 3. Spaced blocks 4 fit the cross-section of the trough whose sides are secured to it by

brads 5 (Fig. 4). The sides of the trough or the bottoms of the blocks or both may be glued to the inside of the box. 6 is a clip or clasp to releasably hold the roll and consists of a strip of springy metal bent as shown to have opposed spring arms to receive and clasp the roll, and a connecting portion by which the clasp is secured by eyelets 7 to the member 8, as best shown in Fig. 4. 65

By thus boxing the rolls in boxes which differ merely in width but not in height for rolls of different diameters, it will be seen from Fig. 1 that they will have an even-topped satisfactory appearance on the shelf 70 of a cabinet or if not in a cabinet, will stack nicely in even, stable layers.

What I claim is:—

1. Means for boxing music rolls of different diameters, comprising a plurality of 75 individual boxes for the rolls, said boxes having widths varying with the diameters of the rolls, but all having the same height corresponding to that for the largest roll, whereby all of the boxes may be arranged 80 side by side in a horizontal row with their tops all occupying a common horizontal plane, or may be stacked uniformly upon one another in even, stable layers.

2. A box for a music-roll and the like 85 said box having a greater outside height than width and a raised bottom in said box comprising an inverted trough-like member inserted therein and blocks fitting across said trough. 90

3. A box for a music-roll and the like having a height corresponding to a roll of large diameter but a width corresponding to a roll of small diameter, and a raised bottom in said box to support the contained roll 95 adjacent the opening of the box and a clip mounted on said bottom for releasably clasping the roll.

4. A box for a music-roll and the like having a height corresponding to a roll of large diameter but a width corresponding to a roll of small diameter, and a raised bottom in said box to support the contained roll adjacent the opening of the box and a clip mounted on said bottom for releasably clasping the roll, and blocks under said raised bottom. 105

5. A box for a music-roll and the like having a height corresponding to a roll of large diameter but a width corresponding 110

to a roll of small diameter, and a raised bottom in said box to support the contained roll adjacent the opening of the box and a clip mounted on said bottom for releasably clasping the roll, and blocks under said raised bottom severally located at its ends and under said clip.

6. Means for boxing music-rolls of different diameters, comprising a plurality of 10 individual boxes for the rolls, said boxes having widths varying with the diameters of the rolls, but all having the same height corresponding to that for the largest roll, whereby all of the boxes may be arranged 15 side by side in a horizontal row, with their tops all occupying a common horizontal plane, or may be stacked uniformly upon one another in even, stable layers; the boxes for the smaller rolls having means to support the contained rolls adjacent the openings of the boxes.

7. A box for a music-roll or the like, having a greater outside height than width, a raised bottom in said box; to support the 25 contained roll in position adjacent the opening of the box and releasable roll-holding means associated with said raised bottom.

8. A box for a music-roll or the like, having a greater outside height than width; 30 a raised bottom in said box for supporting the contained roll in position adjacent the opening of the box, said bottom comprising an inverted trough-like member inserted therein; and releasable roll-holding means

in said box associated with said raised bottom.

9. A plurality of superposed layers of boxes containing individual music rolls of different diameters, the tops of the boxes of each layer occupying a common horizontal 40 plane, all of the boxes having a uniform height corresponding to that for the music roll of largest diameter and the boxes having widths varying with the diameters of the 45 music rolls.

10. As an element of a stack of superposed layers of boxes containing individual music rolls of different diameters, the tops of the boxes of each layer occupying a common horizontal plane, a unit comprising a box and 50 a music roll therein, the height and width of such box conforming with the diameter of the roll which it contains, and another box and music roll therein, the latter music roll being of smaller diameter than that of the 55 first mentioned box of the unit and having a width conforming with the diameter of the music roll which it contains and having a height conforming with the height of the first mentioned box of the unit.

In testimony whereof I have signed my name to this specification, in the presence of two subscribing witnesses, this 18th day of January, 1915.

EDWIN BURRITT PROUDFIT.

Copies of this patent may be obtained for five cents each, by addressing the "Commissioner of Patents,
Washington, D. C."

It is hereby certified that in Letters Patent No. 1,317,035, granted September 23, 1919, upon the application of Edwin Burritt Proudfit, of Westfield, New Jersey, for an improvement in "Means for Boxing Music-Rolls," errors appear in the printed specification requiring correction as follows: Page 1, line 9, beginning with the article "the" strike out all to and including the word "therein," line 11, and insert the words *means for boxing music rolls*; same page, line 51, for the word "mount" read *mouth*; and that the said Letters Patent should be read with these corrections therein that the same may conform to the record of the case in the Patent Office.

Signed and sealed this 11th day of November, A. D., 1919.

[SEAL.]

M. H. COULSTON,

Acting Commissioner of Patents.
